OF 126,615

EX

DESIGN FOR STAIR-RODS.

Design No. 6,615, dated April 29, 1873

UNITED STATES PATENT OFFICE.

WILLIAM T. MERSEREAU, OF ORANGE, NEW JERSEY.

DESIGN FOR STAIR-RODS.

Specification forming part of Design No. 6,615, dated April 29, 1873; application filed April 17, 1873.

To all whom it may concern:

Be it known that I, WILLIAM F. MERSEREAU, of Orange, Essex county, New Jersey, have originated and produced a new and original Design for Stair-Rod Tips; and that the following is a specification of the same, reference being had to the accompanying photographic impression:

The nature of my design consists in making the tips or end pieces between which the rod is held, one of the shape and appearance of the point on upper end of an arrow, and the other of the shape and appearance of

the feathered or lower end of an arrow, so that when a round rod is placed between the tips the general appearance of the rod shall be that of an arrow.

Having now set forth my invention, what I claim as new, is—

The design for stair-rod tips, as shown and described.

W. T. MERSEREAU.

In presence of—

A. SIDNEY DOANE,
FRAS. DOMINICH.
